UNITED STATES PATENT OFFICE.

GEORGE A. HATTERSLEY, OF NORWOOD, OHIO, ASSIGNOR TO VICTOR SAFE & LOCK CO., OF CINCINNATI, OHIO, A CORPORATION OF OHIO.

SAFE-CLOSING MEANS.

No. 916,704.

Specification of Letters Patent. Patented March 30, 1909.

Application filed May 18, 1907. Serial No. 374,514.

To all whom it may concern:

Be it known that I, GEORGE A. HATTERSLEY, a citizen of the United States, and residing at Norwood, Hamilton county, State 5 of Ohio, have invented certain new and useful Improvements in Safe-Closing Means; and I do declare the following to be a clear, full, and exact description of the invention, attention being called to the accompanying 10 drawing, with the reference characters marked thereon, which form also a part of this specification.

This invention concerns improvements in the construction of safes of a type illustrated 15 in Patent No. 905,180, and in which patent the construction of certain means is described for holding the door of a safe in position when seated to close the opening provided for it in the safe-body.

20 The invention relates to certain improvements which are applicable to the invention described in said patent, so that one may be used in connection with the other.

In the following specification and particularly pointed out in the claims at the end 25 thereof, is found a full description of my invention, together with its parts and manner of construction, which latter is also illustrated in the accompanying drawing, in 30 which:—

Figure 1, shows in front-view a customary safe with its circular door partly open. Fig. 2, is a side-view of the safe shown in the preceding figure with parts partly broken away. 35 Fig. 3, is a sectional detail view of a part of the closing-means.

In the drawing, A represents the safe-body, and a, is the front-wall thereof. B is a circular door-opening within this front-wall. 40 The surface of this latter which surrounds the opening, and forms the seat for a door is shaped to form a tapering jamb b. C, is the circular door fitted to this opening, its edge c, being tapering and fitted to seat against 45 the tapering jamb b, within the opening. This door is carried in a ring or circular frame D, in which it is supported for rotation in a manner customary in screw-door-safes. The ring hangs between vertically aligned trun- 50 nion-bearings d, formed on the usual crane-frame E, which is supported by hinges e, on the front-side of the safe-body. The door, for opening or closing, is manipulated by a handle F, on the crane-frame whereby it is 55 swung to or from its opening. For holding

the door to its seat in this opening, I provide a screw-connection, the complementary parts of which are provided on the tapering surfaces of the door and its jamb respectively. By preference I use a plurality of threads 60 which are equally divided around the circumference and have shown two, which start and terminate at points diametrically opposite each other. The circumferential extent of the threads may be so that they 65 pass partly or entirely around the surfaces on which they are provided. When one thread is used it should at least pass once around the entire circumference so that the door has a screw-connected bearing all around. In the 70 form shown, the two threads are so arranged that they together provide such a continuous bearing.

Since the tapering surfaces of the door and its jamb are closely fitted to each other 75 by a ground joint, the door being ground into its opening, it becomes necessary to provide the projecting or male part of the thread in form of a separate member which is placed in position after the door has been 80 ground to its seat. In the case illustrated I provide two of these members and designate them hereafter as tongues G, each appropriately shaped and curved to a screw-pitch and which tongues are rigidly secured 85 in grooves g, provided for them. These tongues in the present case being provided in the door-jamb, said grooves are located accordingly in said jamb, the tongues after insertion projecting above the surface there- 90 of. The complementary grooves which receive the projecting part of these tongues when the door is closed are provided in the tapering side of the door as shown at H, H, and have also a screw-pitch corresponding 95 to the pitch of the tongues. These grooves run out to the open as shown at h, h, where they permit the tongues to start their entrance. This entry of the tongues is caused by rotation of the door which is done in the 100 usual manner applied in screw-door-safes. When screwed home, the door is firmly held in its opening against movement in an axial direction. It is locked in this closed position by the usual bolt - mechanism (not 105 shown) provided in the door, the ends of the bolts entering sockets K, one socket only appearing in Fig. 2. The bolts may be operated by a time-lock mechanism or otherwise. It is essential, when the door is fully screwed 110

home, that the ends of these bolts have arrived opposite these sockets K, so as to be capable of entering them. This requires adjustment, absolutely accurate, of the position of the tongues within their complementary grooves with reference to the position of the bolts and their sockets. Under the present conditions and particularly with an integral male-thread the obtention of this adjustment is connected with many difficulties and requires much time-consuming labor by filing and grinding to fit the exact position. The provision of the male-thread in form of an adjustable member which may be shifted length-wise in its groove goes far toward solving this perplexing problem. A tongue may be shifted length-wise in its groove to the proper position, and if too long, it may be cut off, the vacant space in groove g, being filled out by means of a wedge-shaped insert L, as shown in Fig. 3, which is fitted into this space and serves to hold the tongue firmly in position. The same may be done if by use and wear the proper fit should be lost when this insert may be withdrawn and after the tongue has been adjusted, another wedge is inserted. It permits also changes in the size (width), of the tongue and shape of its pitch if such is necessary. All the work for fitting, and finishing now done by cutting or filing, may be done by grinding and since no machine-tool-work has to be done, this construction is excellently well adapted for use on safes which are made of non-machinable metal like manganese steel for instance. In such case, tongues G, may also be made of the same material like the body of the safe and ground to shape.

Having described my invention, I claim as new:

1. In a safe having a circular door-opening with a tapering door-jamb and a circular door fitted to this jamb, the opposite surfaces of both being each provided with complementary screw-pitched grooves which, when the door is seated, are opposite each other, tongues adapted to occupy simultaneously these opposite grooves, they being shorter than the grooves to permit adjustment for being fitted, and means provided in the grooves in one of the surfaces to fill the space therein which is not occupied by the tongues, and serving for the purpose to hold these latter rigidly in position. 40

2. In a safe having a circular door-opening with a tapering jamb which is provided with screw-pitched grooves, tongues fitted to these grooves and projecting above them, the grooves being longer to permit the tongues to be adjusted lengthwise in them if necessary for fitting, wedge-shaped inserts to fill the space in these grooves not occupied by the tongues and serving to rigidly secure them in these grooves after adjusted, and a door fitted to the door-opening and provided with grooves in its tapering edge complementary to the tongues and adapted to receive their projecting part. 50
